DESIGN FOR A HAT-ADVERTISING CARRIAGE.

SAMUEL JACKSON, JR., OF ROXBURY, MASSACHUSETTS.

Design No. 2,509, dated November 27, 1866.

SPECIFICATION.

TO ALL WHOM IT MAY CONCERN:

Be it known that I, SAMUEL JACKSON, Jr., of Roxbury, in the county of Norfolk, and State of Massachusetts, have produced a new and original design for a Hat-Advertising Carriage; of which the following is a full, clear, and exact description, reference being had to the accompanying drawing, making part of this specification.

The annexed drawing shows a perspective elevation of a carriage, with four ordinary wheels, and springs, to which is attached the body of the carriage, A A, which can be made of iron, wood, or other material, the form of the said body being that of a hat. Its form serves as an advertisement for any firm doing a hat and cap business, who may adopt this particular form of carriage.

What I claim, is the design for an advertising carriage as shown and described.
